No. 722,826.

PATENTED MAR. 17, 1903.

J. H. FASSETT & J. E. WARREN.

PENCIL SHARPENER.

APPLICATION FILED AUG. 12, 1902.

NO MODEL.

UNITED STATES PATENT OFFICE.

JAMES H. FASSETT, OF NASHUA, AND JOHN E. WARREN, OF GREENFIELD,
NEW HAMPSHIRE.

PENCIL-SHARPENER.

SPECIFICATION forming part of Letters Patent No. 722,826, dated March 17, 1903.

Application filed August 12, 1902. Serial No. 119,376. (No model.)

To all whom it may concern:

Be it known that we, JAMES H. FASSETT, of Nashua, and JOHN E. WARREN, of Greenfield, in the county of Hillsboro and State of New Hampshire, citizens of the United States, have jointly invented a new and useful Improvement in Pencil-Sharpener, of which the following is a specification, reference being had to the accompanying drawings.

10 Our invention relates to devices for sharpening pencils, and has for its object to provide a pencil-sharpener which is efficient in use and cheap in construction and which insures that the lead of the pencil will not be broken during the operation of sharpening.

15 Our invention consists in the pencil-sharpener and in the combinations of mechanisms hereinafter described and claimed.

One feature of our invention lies in the 20 means devised for giving automatically to the rotary sharpening device a progressive longitudinal movement toward the pencil. By these means the cutting operation is performed without undue shock with its attendant splintering of the wood and breaking of the lead. Moreover, the control of the feeding of the sharpening device to the pencil is taken from the operator and made automatic, positive, regular, and gradual. Pencil-sharpener 25 are often used by school-children and other unskilled operators, and the provision made for taking from them the control of the feed and for making it automatic results in many obvious advantages.

30 Another feature of our invention resides in the means provided for supporting the pointed end of the pencil against the sharpening device. In our new pencil-sharpener these means are made yielding and comprise a piece 35 of spring metal so secured in the frame that its free end bears against and supports the pointed end of the pencil. The support being yielding, a slight vibratory motion is permitted the pointed end of the pencil, with the 40 result that the lead is preserved intact and that a smooth sharpened end is produced on the pencil.

A third feature of our invention consists 45 in the cap for covering the cutting-knives. 50 This cap is preferably secured to the frame and is provided with an aperture to permit

access to the cutter-plate-securing screw, with an aperture through which fall the wood and lead removed by the sharpening device and with a slot for the entrance of the pointed 55 end of the pencil.

A fourth feature of our invention is the means devised for limiting the inward longitudinal movement of the pencil, so as to position the pencil relatively to the sharpening 60 device. These means comprise an L-shaped piece of flat spring metal secured in a slot in the cap. The pencil is forced in lengthwise until its pointed end strikes the free end of the spring metal. By these means the pencil is 65 adjusted automatically in position, and nothing is left to the judgment of the operator. It results from this that the pencil is automatically and uniformly held in the best position for being properly sharpened.

70 A fifth feature of our invention is found in means provided for holding the pencil securely while it is rotated. These means are a series of spring-metal strips secured to the hollow rotary shaft, through which the pencil is passed. This device is simple and efficient.

75 In the drawings illustrating the principle of our invention and the best mode in which we have contemplated applying that principle, Figure 1 is a side elevation of our new pencil-sharpener, a part of the mechanism being broken away for greater clearness. Fig. 2 is a sectional view on line 2 2 of Fig. 1. Fig. 3 is a detail sectional view herein- 80 after referred to. Fig. 4 is a central sectional view of the cap, and Fig. 5 is a detail showing the cam ratchet-wheel in edge elevation.

85 Journaled in the frame *a* is the shaft *b*, fast 90 upon which are the driving-gear *c* and the beveled gear *d*, preferably formed integral with said driving-gear *c*. The beveled gear *d* meshes with the beveled gear *e*, mounted in the standards *f* and fast upon a hollow shaft 95 *g*, adapted to receive the pencil *g'*, which is held firmly in said hollow shaft by means of the spring-steel clasps *h h*. The driving-gear *c* meshes with the pinion *j*, keyed at *k* to one end of the shaft *l*, which shaft is journaled in the frame *a* and is free to slide longitudinally in its bearings. (See Figs. 2 and 100

3.) The other end of said shaft *l* is formed with a disk *m*, to which the cutter-plate *n* is detachably secured by the thumb-screw *o*. Free to rotate on the journal-bearing of the 5 shaft *l* is the cam ratchet-wheel *p*. (Shown in Fig. 5.) The edge of the hub *q* of said ratchet-wheel *p* is a cam-surface, against which abuts one end of a pin *r*, the other end of which bears against the disk *m*. A spiral 10 spring *s* is interposed between the inner face of the pinion *j* and the opposed face of the journal-bearing of the shaft *l*. (See Fig. 3.) A collar *t*, secured to the said journal-bearing, serves as a suitable means to hold the 15 cam ratchet-wheel *p* in place on said journal-bearing, which therefore serves as a shaft for said cam ratchet-wheel *p*.

Secured to the frame *a*, near the top thereof, is the cap or cover *u*, slotted at *v* and formed 20 with a central opening, through which projects the head of the thumb-screw *o*. (See Fig. 4.) Secured to the cap *u* is a flat L-shaped spring *w*, the free end *x* of which projects inwardly to form a bearing for the point 25 of the pencil, and thereby serves to position the pencil properly relatively to the cutter. A flat spring *y* is secured in an upright position to the frame *a* and gives the pointed end of the pencil a yielding support, which prevents 30 the lead from being broken.

The operation of our new pencil-sharpener will now be readily understood. By means of the handle *z* the driving-gear *c* is turned, thereby turning the pinion *j* and rotating the 35 cutter-plate *n* with its integral radial knives. Also the beveled gear *e* is caused to rotate, thereby rotating the pencil, which passes through the hollow shaft *g* and is held firmly clasped by the spring-clasp *h*. Once in each 40 revolution of the driving-gear *c* the stud *i* engages a tooth on the cam ratchet-wheel *p*, and thereby the said cam ratchet-wheel is given a step-by-step rotation. The cam edge on the hub *q* of said cam ratchet-wheel causes 45 the pin *r* to press forward (or toward the pencil) the disk *m* with its attached cutter-plate *n*. Thus the knives are fed gradually to the pencil, and the pencil is sharpened progressively and without shock and splintering of the 50 wood. This is an important feature, since it insures that the lead of the pencil will not be broken and that a fine surface will be given to the sharpened end. The flat upright spring *y* allows the pointed end of the pencil to yield 55 and to vibrate, and thereby prevents the lead of the pencil from being broken, as would probably be the case were a rigid mounting used.

What we claim is—

60 1. In a pencil-sharpener, the combination of a pencil-holding mechanism; a sharpening device; a driving mechanism therefor; means driven by said driving mechanism for feeding said sharpening device to the pencil; and means for automatically restoring said sharpening device to its initial position.

2. In a pencil-sharpener, the combination

of a driving mechanism; a longitudinally-slidable, cutter-carrying shaft driven thereby; and mechanism driven by said driving mechanism for reciprocating said cutter-carrying shaft longitudinally. 70

3. In a pencil-sharpener, the combination with a supporting-frame and a driving mechanism mounted therein, of a rotatable member formed with a cam-surface, and driven by said driving mechanism; a cutter-carrying shaft; a cutting device on said shaft; means interposed between said shaft and said rotatable member by which said shaft is automatically moved longitudinally in said frame; and a pencil-holding device. 80

4. In a pencil-sharpener, the combination with a supporting-frame and a driving mechanism mounted therein, of a longitudinally-slidable cutter-carrying shaft rotated by said mechanism; a cutting device on said shaft; a pencil-holding device rotated by said driving mechanism; a ratchet-wheel formed with a cam and rotated by said driving mechanism; 85 means interposed between said ratchet-wheel and said shaft whereby the rotation of said ratchet-wheel causes said cutter-carrying shaft to move longitudinally toward the pencil; and means for restoring said cutter-carrying shaft to its initial position. 90

5. A pencil-sharpener made up of the following instrumentalities; viz., a rotatable pencil-holder; a sharpening device; a longitudinally-slidable shaft upon which said device 100 is mounted; mechanism for reciprocating said shaft to feed the sharpening device to the pencil gradually and to cause it to recede therefrom when the sharpening operation is finished; and a driving mechanism. 105

6. A device for feeding a sharpening device to the pencil in a pencil-sharpener comprising a ratchet-wheel formed with a cam-surface; means connecting said ratchet-wheel with a longitudinally-slidable shaft; said longitudinally-slidable shaft; a sharpening device on 110 said shaft; and a driving mechanism.

7. In a pencil-sharpener, the combination of a supporting-frame; a pencil-holding mechanism; a sharpening device; a driving mechanism therefor; a cap for covering the sharpening device; and a spring member mounted 115 on said cap for positioning the pencil.

8. In a pencil-sharpener, the combination of a supporting-frame; a driving mechanism; 120 a pencil-holding mechanism; a rotary sharpening device; means for reciprocating said device to and from the pencil; a cap formed with a slot; and a spring in said slot for positioning the pencil relatively to the sharpening device. 125

9. In a pencil-sharpener, the combination of a supporting-frame; a driving mechanism; a pencil-holding mechanism; a sharpening device; and a spring member for limiting the 130 inward longitudinal movement of the pencil to position the pencil relatively to said sharpening device.

10. In a pencil-sharpener, the combination

of a supporting-frame; a driving mechanism; a pencil-holding mechanism; a sharpening device; means for reciprocating said device to and from the pencil; and means for limiting 5 the inward longitudinal movement of the pencil to position the pencil relatively to said sharpening device.

11. The combination in a pencil-sharpener of a sharpening device, a feeding mechanism 10 for feeding said sharpening device to the pencil, a rotary pencil-holding device, and a driving mechanism which actuates said sharpening device, feeding mechanism, and pencil-holding device.

15 12. In a pencil-sharpener, the combination with a driving mechanism; a rotary sharpening device; and a rotary pencil-holding device; of a yielding member mounted upon a supporting-frame and adapted to form a

yielding support for the end of the pencil 20 while said pencil end is being sharpened; and said supporting-frame.

13. The combination in a pencil-sharpener of a supporting-frame and a driving mechanism mounted therein with a longitudinally- 25 slidable cutter-carrying shaft and means operated by said driving mechanism to reciprocate said shaft lengthwise.

In testimony whereof we have hereunto set our hands, at Peterboro, in the county of Hills- 30 boro and State of New Hampshire, this 8th day of August, in the presence of two witnesses.

JAMES H. FASSETT.
JOHN E. WARREN.
